(57) **CLAIM**

The ornamental design for a shoe outsole, as shown and described.

DESCRIPTION

FIG. 1 is a front perspective view of a shoe outsole showing my new design;

FIG. 2 is a rear perspective view thereof;

FIG. 3 is an enlarged view of FIG. 1 with some unclaimed subject matter omitted; and,

FIG. 4 is an enlarged view of FIG. 2 with some unclaimed subject matter omitted.

The photographic area is claimed. The broken lines immediately adjacent to the photographic area represent unclaimed boundaries of the design. The broken lines showing the remainder of the shoe are for environmental purposes only and form no part of the claimed design.
